Specification for Design.

Patented Nov. 26, 1912.

Application filed February 10, 1911. Serial No. 607,869. Term of patent 14 years.

To all whom it may concern:

Be it known that I, ARTHUR A. FRIESTEDT, a citizen of the United States, residing at Chicago, in the county of Cook and State of Illinois, have invented a new, original, and ornamental Design for a Note-Sheet Spool End, of which the following is a specification, reference being had to the accompanying drawings, forming part thereof.

On the drawings Figures 1, and 2 repre-

sent an end elevation, and a perspective view respectively of a note-sheet spool end, showing my new design.

I claim:

The ornamental design for a note-sheet spool end, as shown.

ARTHUR A. FRIESTEDT.
